UNITED STATES PATENT OFFICE.

FRANK W. BACON, OF LOS ANGELES, CALIFORNIA.

DISTANCE-CHART.

1,300,808.

Specification of Letters Patent. Patented Apr. 15, 1919.

Application filed April 29, 1918. Serial No. 231,490.

To all whom it may concern:

Be it known that I, FRANK W. BACON, a citizen of the United States, residing in Los Angeles, in the county of Los Angeles 5 and State of California, have invented a new and useful Distance-Chart, of which the following is a specification.

This invention pertains to charts designed for giving the distance from station to station along a particular route and an object of the invention is to render clear at a glance the distance between the terminal stations on a given route or between either of said terminal stations and any one of the 15 intermediate or way stations.

Other objects and advantages will appear in the subjoined detail description.

The accompanying drawing illustrates the invention and the figure is a plan view of 20 the chart.

The route on which the various stations are located may be a railroad route or highway route and in the instance shown in the drawing, the routes are boulevard or highway routes. 25

The term "station" employed herein represents any particular point that it may be desired to designate on the chart. In the instance shown in the drawing two routes 30 are indicated, the coast and inland routes from Los Angeles to San Diego. The chart may be read, for the coast route, by holding it in one position and then by reversing the chart end for end it may be read for the 35 inland route.

The names of stations are indicated at *a* and alined with said names of stations are characters *b* in columns representing different distances in any preferred unit of measurement. Each character *b* in the first column represents the distance between the starting station and the station of which the name appears opposite said character, in the instance shown "Los Angeles" being the 45 starting station. Each character *b* in the second column represents the distance between the second station and the station of which the name appears opposite said character, in the instance shown "Pio Pico Old 50 Home" being the second station. Each character *b* in the third column represents the distance between the third station from the starting station and the station of which the name appears opposite said character, in 55 this instance "X Road for La Habra and Brea." Likewise the fourth column of

characters *b* is read in conjunction with the name of the fourth station, the fifth with the name of the fifth station, the sixth with the name of the sixth station, and so on. 60

For convenience in reading the charts it may be desirable to designate the various columns by the names of the stations as indicated at *c* in alinement with said columns. 65

From the foregoing it is clear that the columns of characters *b* decrease in length from left to right of the chart, the number of distance indicating characters in each column decreasing by one. At the head of each column is a naught, said naught designating the starting point for reading the distances. 70

To make clear the use of the chart, it may be assumed that the starting station is "Los Angeles," as indicated in the drawing, that 75 the finish terminal station is "San Diego," that the intermediate stations are as given in the drawing, and that the characters *b* are the distances in miles. By the use of the first column to the right of the stations, 80 it is clear that the distance between "Los Angeles" and any one of the other stations, reached successively in the trip from "Los Angeles" to "San Diego," is designated by the appropriate number representing miles. 85 For instance, the distance from "Los Angeles" to "Oceanside" is 90 miles as indicated in the chart and the distance from "Los Angeles" to "San Diego" is 133 miles. 90

If we wish to know the distance, for instance, from "Oceanside" to "San Diego," we trace down the column designated "Oceanside," beginning at naught opposite "Oceanside," and find at the bottom of the column opposite "San Diego" the number 95 "43" which is the distance required in miles. In this column designated "Oceanside" are characters representing the distances between "Oceanside" and "Carlsbad Station," the distance being three miles; from "Oceanside" to "Cardiff," 14 miles, and so on. 100

It will be seen that the number in each successive column reading from left to right opposite each name of a station is the difference between the number in the next preceding column opposite said name of a station and the number appearing at the head of said next preceding column; for instance, 105 61 appears in the fourth column opposite "Oceanside," and 68 is the number in the third or next preceding column opposite "Oceanside." The number 7 is at the head 110

of the third column and subtracting 7 from 68 leaves 61, which is the number of miles from "Anaheim" to "Oceanside." This is the principle on which the chart is constructed. Or stated differently, the number in each column opposite any given name of a station is as much less than the number in the preceding column opposite the same name of a station as the number of miles 10 from the station designating the succeeding column to the next preceding station. Thus 45 opposite "Oceanside" is the distance in miles from "Oceanside" to "Irvine Station," and this distance is as much less than 54 in 15 the preceding column opposite "Oceanside" as the indicated mileage from "Santa Ana" to the next succeeding station, "Irvine Station," which is 9 miles.

The stations and distance indicating 20 characters are arranged in separate sets, one set being for each route.

The characters of each set are arranged in the form of a triangular block and the stations and distance indicating characters 25 of one set are inverted with reference to the stations and distance indicating characters of the other set.

I claim:

1. A distance chart having names of stations arranged in a column, and distance indicating characters located opposite said names of stations, in successive columns, the number of distance indicating characters in each column decreasing by one and the value 35 of the last distance indicating character appearing opposite any given name of a station being as much less than the value of the character appearing in the same column opposite the next succeeding name of a station 40 as is the distance from said first named station to the said succeeding station.

2. A distance chart having names of stations arranged in columns, and distance indicating characters located opposite said names of stations, in successive columns, there being two sets of names of stations and distance indicating characters arranged 45 separately and those of one set being inverted with reference to those of the other set and each set of characters being in the form of a triangular block, in each set the number of distance indicating characters 50

Copies of this patent may be obtained for five cents each, by addressing the "Commissioner of Patents, Washington, D. C."

in each column decreasing by one and the value of the last distance indicating character appearing opposite any given name of 55 a station being as much less than the value of the character appearing in the same column opposite the next succeeding name of a station as is the distance from said first named station to the said succeeding station. 60

3. A distance chart having names of stations arranged in a column, and distance indicating characters located opposite said names of stations, in successive columns, the difference between the value of the distance 65 indicating character appearing in any column opposite any given name of a station and the value of the distance indicating character appearing in the same column opposite the next succeeding name of a station 70 being equal to the value of the last distance indicating character appearing opposite the name of said succeeding station.

4. A distance chart having names of stations arranged in a column, and distance indicating characters located opposite said names of stations, in successive columns, the number of distance indicating characters in each column decreasing by one and the characters in any given column denoting the 80 distance respectively from the station named opposite the head of said given column to the succeeding named stations.

5. A distance chart having names of stations arranged in a column, and distance indicating characters located opposite said names of stations, in successive columns, the values of the distance indicating characters opposite any given name of a station being as much less than the values of the distance 85 indicating characters in the same columns respectively appearing opposite to the next succeeding name of a station as the distance from any given preceding named station to the given station is less than the distance 90 from said given preceding named station to said succeeding named station.

Signed at Los Angeles, California, this 20th day of April, 1918.

FRANK W. BACON.
